TYPEWRITING MACHINE

Albert B. Schuyler, Rochester, N. Y., assignor to
 International Business Machines Corporation,
 New York, N. Y., a corporation of New York

Application May 18, 1942, Serial No. 443,393

4 Claims. (Cl. 197—63)

This invention relates to typewriting machines.

An object of the present invention is to provide means for setting the marginal stops of a typewriting machine.

Another object is to provide a marginal stop setting mechanism which enables either the right or left hand marginal stop of a typewriting machine to be set by means of a single setting lever conveniently located at one end of the carriage.

An object is to provide a marginal stop setting mechanism which is simple and has few working parts.

Other objects of the invention will be pointed out in the following description and claims and illustrated in the accompanying drawing, which disclose, by way of example, the principle of the invention and the best mode, which has been contemplated, of applying that principle.

In the drawing:

Fig. 1 is a plan view of the marginal stop setting mechanism as viewed from the rear of the machine.

Fig. 2 is a rear elevation.

Fig. 3 is an elevation of a portion of the right hand end of the carriage with certain parts in section.

Fig. 4 is a view similar to Fig. 3, but showing certain of the parts in the operated position.

Fig. 5 is a vertical longitudinal section of the left hand marginal stop.

The numeral 10 in the drawing designates the side plates of a typewriter carriage which are rigidly joined together by a channel-shaped member 11, which is formed with grooves to accommodate the usual anti-friction roller trucks 12 by means of which the carriage is supported upon the rails. In Figs. 1, 2 and 3 the reference numeral 13 designates the usual rear rail.

Mounted between the side plates 10 of the carriage is the marginal stop rack 14 having its upper edge provided with teeth to correspond with the teeth in the usual escapement rack (not shown). Slidably mounted on the escapement rack 14 is the right hand marginal stop 15 and the left hand marginal stop 16 which determine the right and left hand margins respectively of a work sheet. The marginal stops 15 and 16 are similarly constructed but their corresponding parts are symmetrically located with respect to the center of the carriage; accordingly, a description of one will suffice for both.

In Fig. 5 there is shown in vertical section the left hand marginal stop 16. This stop comprises two side pieces 16a in the form of flat plates which are spaced apart by a stop block 16b and a

spacer block 16c, these parts being located below and above the edges of the marginal stop rack 14, the block 16c riding upon the tips of teeth on the rack. Pivoted on a rivet 16d, between the plates 16a, is a marginal stop latch block 16e which is cut away to accommodate the spacing block 16c. The end of the latch block 16e opposite the pivot 16d is formed with a number of teeth 16f corresponding to the teeth in the rack 14 and also has a pin 16g to which is anchored a spring 16h. This spring is anchored to a pin 16i most clearly shown in Fig. 3 attached to one of the plates 16a and normally holds the toothed portion 16f in engagement with the teeth of the rack 14. Fig. 5 shows the latch block in disengaged position while the other views show the latch block in engaged position locking the marginal stops to the rack 14. The parts of the right hand marginal stop 15 are designated with the number 15 and the corresponding letters where these parts are visible in the drawing. The pins 15g, 16g are provided with mushroom shaped heads 15j, 16j for a purpose to be made clear later. During the operation of typing, the marginal stops 15 and 16 remain locked to the rack 14 and by their position determine the extent of carriage travel in the usual way.

For the purpose of releasing the marginal stops and resetting them to a new position without lifting the paper table and reaching behind it to change the position of the stops, there is provided means including an operating handle within convenient reach of the operator's right hand. This setting means includes a shaft 17 journaled in the carriage side plates 10 and extending parallel with the rack 14 and a short distance to the rear thereof. Secured to this shaft 17 is a universal bar in the form of an angle strip 18, the wider face portion of which extends with its edge underneath the heads 15j, 16j of the pins 15h, 16h. At its right hand end, that is the left hand end with reference to Figs. 1 and 2, the shaft 17 is provided with an arm 19 having a pin 20 extending into a radial slot in an operating lever 21 which is pivoted on a stud 22 carried by the right hand side plate 10 of the carriage. Interposed between the stud 22 and the pin 20 is a wishbone spring 23 which in Fig. 3 tends to push the pin 20 radially of the stud 22 and thereby tends to urge the shaft 17 and universal bar in a counterclockwise direction (Fig. 3). However, this movement is limited by a stop stud 24 on plate 10 which works in a notch formed in the arm 19, the pin 24, in the position of Fig. 3, engaging the side of the arm 19, while in the posi-

tion of Fig. 4, a projection 19a formed by the notch in the arm 19, limits clockwise rotation of the shaft 17 by engagement with the pin 24. Thus, spring 23 acts like a toggle spring to hold the operating arm or lever 21 in either of its set positions.

The side plates 15a, 16a and the stop blocks 15b, 16b of the marginal stops are shaped for cooperation with the lug 25a (Fig. 2) formed in the tabular lever 25 to limit the carriage movement according to the position of the marginal stops. This tabular lever or its equivalent is a usual element in a typewriter and may be of the same form as the one disclosed in Patent No. 1,935,436. However, any other suitable stop member may be employed for the same purpose. As usual, the member 25 may be coupled in some manner to a marginal release key (not shown) to permit the lug 25a to be moved from the path of the stop blocks on the marginal stops to enable the carriage to be moved beyond either of the marginal positions when necessary.

When the right hand marginal stop 15 is brought into engagement with the lug 25a by moving the carriage toward the right hand marginal position, that is to the right in Figs. 1 and 2, the pin 15h is brought directly underneath a notch 26a formed in a plate 26 secured to a bracket 27 which is fastened to the top of the rear rail 13. On the other hand, when the left hand marginal stop 16 is similarly brought into engagement with the lug 25a the pin 16g will be brought underneath a second notch 26b (Fig. 2) in the plate 26.

If it is desired to reset the right hand marginal stop 15 the carriage may be moved by hand to the right hand marginal position, that is to the right in Figs. 1 and 2, as far as it will go as determined by the position of the marginal stop 15 on the rack 14. The lever 21 may now be grasped with the right hand and rocked from the position of Fig. 3 to the position of Fig. 4. This will cause the shaft 17 and the universal bar 18 to rock clockwise and the edge of the wider face of the angle strip, by contacting the enlargement 15j, 16j, will lift both latch blocks 15e, 16e to the position shown in Fig. 5 for the left hand marginal stop. This causes the pin 15g to enter the notch 26a. If now the carriage is moved to right or left with reference to Figs. 1 and 2, the marginal stop 15 will be held against movement and will slide relative to the rack 14. If it is desired to move the marginal stop nearer the edge of the paper so as to increase the length of the line, the carriage will be moved to the right in Figs. 1 and 2 thereby bringing the left hand plate 10 in Fig. 2 nearer to the marginal stop 15 by the required amount. With the carriage held stationary the lever 21 is now pushed back to the position of Fig. 3, thereby allowing the latch block 15e to again lock the marginal stop 15 to the rack 14. While the latch block 16e is also raised by the foregoing procedure, pin 16g cannot enter the notch 26b because of the fact that the marginal stop 16 when properly locked to the notch 26a in the plate 26, will extend opposite the notch 26b. In a similar manner the left hand marginal stop 16 may be reset by moving the carriage to its extreme limit of travel counter to letter spacing movement, that is to the left in Figs. 1 and 2, until the pin 16g registers with the notch 26b before operating the lever 21.

One of the advantages of the stop setting means disclosed herein is its simplicity and ease

of operation since the operating lever for universal bar 18 is located on the right hand end of the carriage for operation by the right hand operator. In the usual operation of a typewriting machine, it is most natural to move the carriage with the right hand since the right hand is usually more dexterous than the left. Since the hand is usually used to move the carriage in resetting the stops, it is more convenient to have the operating lever or key for controlling the stop setting mechanism located at the point where the hand naturally must be placed to move the carriage. When the stops are set by a mechanism controlled by a key adjacent the keyboard both hands must be used or a double movement of one hand is necessary.

Since there are few operating parts in the mechanism, no appreciable extra weight is placed on the carriage. Also no internal connection from the keyboard to the rear of the machine is necessary as is the case when the stops are released by a key adjacent the keyboard. Another advantage is that no springs are needed to draw the marginal stops to the center position prior to moving the carriage to a new position in setting the stops.

It will be readily apparent therefore that the stop setting mechanism disclosed herein has many advantages over prior art structures which are usually more complicated and less convenient to use.

While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

I claim:

1. In combination with the carriage of a typewriting machine, a marginal stop rack mounted on the carriage; right and left hand marginal stops slidably mounted on said rack, each of said stops including a latch member for locking the marginal stops to the rack, each of said latch members carrying a pin for releasing its latch member; means common to both marginal stops and engageable with both of said pins to disengage said latch members from said rack, an operating member for the disengaging means, and means operative when either of the latch members are released with the marginal stops in the margin defining position to engage the pin for the released latch member and hold the marginal stop for the released latch member against movement while the carriage is moved to a new marginal position.

2. In combination with the carriage of a typewriting machine, a toothed marginal stop rack; marginal stops slidably mounted on said rack, each of said marginal stops having a pivoted latch block provided with a toothed portion engaging the teeth in said rack, said toothed portion being provided with a latch releasing projection; a universal bar mounted on the carriage and extending parallel with the marginal stop rack and operatively engageable with said projection, said universal bar when moved engaging said projection to disengage said latch blocks from the rack; and means, into engagement with which the projection on either latch block may be

moved by the universal bar when the carriage is in either margin defining position, to hold the marginal stop defining such position against movement and thereby enable the carriage to be moved to a new marginal position.

3. In combination with the carriage of a type-writing machine, a toothed marginal stop bar, a marginal stop slidably mounted on said bar, said marginal stop having a pivoted latch block provided with a toothed portion engaging the teeth of said rack and spring means to urge the latch block into engagement with the rack, said latch block having a projection by means of which the latch block may be lifted out of engagement with the rack and also having a locking projection, a universal bar pivotally mounted in the carriage and engaging the first named projection, a lever for operating the universal bar to rock the latch blocks out of engagement with the rack, and a locking plate adapted to receive 20 the locking projection of the marginal stop when the latch block is disengaged from the rack with the carriage in its marginal position to permit movement of the carriage to a new marginal position.

25

4. In combination with the carriage of a type-writing machine, a support mounted on the carriage and extending parallel with the line of travel of the carriage; marginal stops adjustably 5 slidably mounted on said support, each of said stops including a member movable relative to the stop to lock the stop in its adjusting position along said support, each member being releasable for adjusting the stop along said support and including a releasing and locking element fixed to such member; a universal bar movably mounted on the carriage and extending parallel with said support, said universal bar engaging the element fixed on the locking members and, when moved, releasing said members to enable the marginal stops to be adjusted along said support; manual operating means for moving the universal bar, and means engaged by said elements when the universal bar is moved by said operating means with the carriage in a given margin defining position to hold the corresponding marginal stop immovable to permit movement of the carriage relative to the marginal stop to a new marginal position.

ALBERT B. SCHUYLER.
